THREAD CUTTER FOR SEWING MACHINES OR THE LIKE

Filed Sept. 17, 1930

Charles W. H' Doubler

UNITED STATES PATENT OFFICE

CHARLES W. H'DOUBLER, OF SPRINGFIELD, MISSOURI

THREAD CUTTER FOR SEWING MACHINES OR THE LIKE

Application filed September 17, 1930. Serial No. 482,552.

The present invention relates to new and useful improvements in thread cutters for sewing machines or the like.

Thread cutters, such as have heretofore been used in connection with sewing machines, are customarily supported on the presser bar or the head block of the machine and, being exposed, are a menace to the operator's fingers if possessed of a sufficiently keen edge to cut the thread effectively. The prior thread cutters are, therefore, usually provided with edges that are so blunt that instead of cutting they break the thread pulled over them. Then too, after the threads have been cut or broken to release the sewed material from the machine, the two ends of the thread supply are left loose and must be caught up and adjusted below the presser foot before a new seam is begun.

It is one of the objects of the present invention to overcome these objectionable features of prior devices of this character. Another object of the invention is to provide a thread cutter for sewing machines or the like, which has a keen thread cutting portion so formed and positioned that the sharp cutting edge thereof cannot come in contact with the operator's fingers.

A further object of the invention is to provide a thread cutter for sewing machines or the like, which is formed and positioned in such manner, that when the thread of a finished seam has been severed from the material or goods, the two ends of the unused thread may be yieldingly retained under the cutter bar in proper and convenient position for the beginning of a new seam.

Still another object of the invention is to provide a thread cutter which is simple and compact in construction, and which is moreover highly efficient in operation.

With the above and other objects in view my invention consists of the improved thread cutter for sewing machines or the like, set forth in the specifications and in the claims annexed to and forming part of this specification.

In the accompanying drawing, also forming part of this specification, I have illustrated two slightly varying examples of ac-

tual embodiments of my invention, constructed according to modes which I have thus far devised for the practical application of the principles thereof, and in which:

Fig. 1 is a front elevation of a special type 55 of sewing machine equipped with the improved thread cutter;

Fig. 2 is a top view of the front end of the same sewing machine showing the improved thread cutter in position on the bed 60 plate portion;

Fig. 3 is an enlarged side view of the improved thread cutter detached from the sewing machine; and

Fig. 4 is an enlarged top view of a slightly 65 modified form of the invention showing the same mounted upon a fragment of the bed plate of a different type of sewing machine from that shown in Figs. 1 and 2.

Referring to the drawing, the numeral 5 indicates the bed plate of a sewing machine. Rising from the bed plate 5 at the rear end thereof is the usual tubular arm 6, which terminates at the front in an integral head 7. The head 7 has mounted therein for reciprocation, a needle bar 8 of usual formation and a presser bar 9. The needle bar 8 carries a needle 10 and the presser bar 9 has a presser foot 11. The needle bar is reciprocable by the usual mechanism (not shown) 80 mounted within the arm whereby stitches are formed in the material being sewed by the needle 10, and a thread 12 cooperates during sewing with a lower thread 13 supported in the bobbin member of a complementary 85 loop taker (not shown) mounted below the sewing plate, to form the stitches.

To permit convenient access to the loop taker, a throat plate 14 covering a usual access opening, is provided, this plate being 90 pivoted to the bed plate 5 by a screw 15.

The bed plate 5 is formed flush with the top of the throat plate at the one side thereof but is machined on the opposite side, as at 16, to provide clearance for swinging the 95 throat plate on its pivot screw 15. In providing such clearance a shoulder 17 is formed running in a straight line from the back edge of the throat plate to the adjacent edge of the bed plate 5. There is also a narrow 100

slot 19 provided in the bed plate, running transversely to and intersecting the shoulder 17, this slot being cut to the same depth as the shoulder. The thread cutter 18 is 5 formed with a downwardly directed hook portion 18' and with a curved cutting portion 21 near its outer end, and also has a lip C at the inner end thereof which is slightly longer than the depth of the slot 19 in 10 which it is seated so that the front end of the medial portion of said thread cutter will, when positioned, stand somewhat above the surface of the bed plate to provide means, coacting with the screw 20, for properly adjusting the frictional tension on the threads 15 which will lie between the bed plate and the flat, resilient rear end portion of the cutter bar adjacent the cutting edge thereof.

The thread cutter 18 is secured to the bed 20 plate 5 and made adjustable thereto by the aforementioned screw 20. It is positioned upon said bed plate with the lip C seated in the slot 19 and the inside edge of the medial portion thereof in direct line with the needle 25 when viewed from the operative side of the machine; and when so positioned, and properly adjusted as to tension, the cutting edge of said cutter will rest closely against the bed plate to protect said cutting edge and the 30 operator's fingers from accidental injury.

The thread cutter is preferably formed of carbonized steel and is suitably tempered, first, to provide resiliency for the body portion thereof, and second, to insure an effective 35 and keen cutting edge on the curved cutting portion 21 when chamfered inwardly as shown at a to position the cutting edge as close as possible to the bed plate.

It has now been made apparent that when 40 a seam has been completed the operator need only draw the two threads 12 and 13, which connect the finished seam with the sewing machine, around and under the outside end of the thread cutter from the rear side thereof. By giving a slight pull the threads will 45 be readily severed and the two unused ends thereof will be yieldingly retained under the resilient body of the cutter bar in correct position for beginning a new seam without further attention and, furthermore, said thread 50 ends will be long enough to tie or sew in when the seam has been finished. Moreover the thread ends are so retained, that when the new 55 seam has been sewed a sufficient distance, the two yieldingly retained thread ends will be automatically drawn free from the thread cutter.

It is to be understood that the gist of the 60 present invention does not reside in any exact shape of the thread cutter but rather in its mode of operation and its disposition relative to the machine. The means by which the two thread ends are yieldingly retained after the 65 threads have been cut loose from the material

being sewed, is also an important feature of the present improvement.

Nor is the application of the present invention to be restricted to the type of sewing machine illustrated and described. I have, 70 therefore, illustrated in Fig. 4 a slightly modified form of the invention wherein the thread cutter is mounted upon a fragment of the bed plate 5 of a sewing machine which is not necessarily provided with a shoulder 75 adapted to be utilized in connection with the thread cutter previously described.

The improved thread cutter as illustrated in Fig. 4 is similar to the one already described, excepting that the hook portion 18' is eliminated, and a slight difference is introduced in the chamfer, shown at b. This chamfer is, however, still formed to position the cutting edge at the bottom of the curved cutting portion of the thread cutter, close to 85 the bed plate.

In this modification, as in the first described device the thread cutter 18 is mounted flat upon the bed plate by the screw 20, the lip C resting in the slot 19, and the back edge 90 of the thread cutter lying in approximate alignment with the needle 10 when viewed from the operating side of the sewing machine.

From the foregoing description, it will be 95 noted that the invention provides a thread cutter especially adapted for use in connection with sewing machines or the like, which is simple and compact in construction and which is moreover highly efficient in operation. The improved device not only insures 100 maintenance of a keen cutting edge without danger to inquiring individuals handling the machine, but also maintains the cut ends of threads in most effective condition for subsequent 105 operation of the machine. The thread cutter is moreover out of the way of fabric being worked upon, and may be manufactured and applied to machines at but slight cost.

It should be understood that it is not desired to limit the invention to the exact details of construction herein shown and described, for various modifications within the scope 110 of the claims may occur to persons skilled in the art.

What I claim as my invention is:

1. In combination with a thread utilizing machine having a presser foot, a thread cutter comprising a flat resilient member secured to the frame of said machine entirely 120 to the rear of the presser foot and having a cutting edge disposed on the outer side edge of said member closely adjacent to said frame.

2. In combination with a sewing machine 125 having a presser foot, a thread cutter for the needle and bobbin threads of said machine comprising a resilient member adjustably secured to the frame of said machine entirely 130 to the rear of the presser foot and having a 135

cutting edge disposed on the outer side edge of said member closely adjacent to and approximately parallel with said frame.

3. In combination with a thread utilizing machine having a presser foot, a thread cutter comprising a resilient member adjustably secured to the frame of said machine entirely to the rear of said presser foot and having a cutting edge disposed on the outer side edge of said member closely adjacent to said frame, said member being formed to hold the end of a cut thread in proper position for subsequent operation of said machine.

15 4. In combination with a sewing machine having a presser foot, a thread cutter for the needle and bobbin threads of said machine comprising a flat resilient member secured to the frame of said machine entirely to the rear of the presser foot of the machine and having a cutting edge disposed on the outer side edge of said member approximately parallel and closely adjacent to said frame, said member being formed to hold the end 20 of a cut thread in proper position for subsequent operation of said machine.

5. In combination with a sewing machine having a presser foot, a thread cutter for the needle and bobbin threads of said machine comprising a member secured to the work supporting surface of said machine substantially in the plane of travel of the material operated upon by said machine and entirely to the rear of the presser foot 30 of said machine, said member having a cutting edge disposed on the outer side edge thereof approximately parallel and closely adjacent to said surface.

6. In combination with a thread utilizing machine having a presser foot and a frame provided with a slot, a thread cutter positioned to the rear of the presser foot and comprising a member having a down turned front end portion coacting with said slot and 40 having a medial portion secured to said frame, the opposite rear end portion of said member being provided with a cutting edge disposed on the side edge of said member closely adjacent to said frame.

50 7. In combination with a thread utilizing machine having a presser foot and a frame provided with a slot, a thread cutter positioned to the rear of the presser foot and comprising a member having a down turned front end portion coacting with said slot and 55 having a medial portion secured to said frame, the opposite rear end portion of said member being resiliently biased toward said frame and having a cutting edge disposed 60 on the side edge thereof directly adjacent and approximately parallel to said frame.

8. In combination with a sewing machine having a presser foot and a frame provided with a slot extending transversely of the 65 direction of travel of material past the needle

thereof, a thread cutter positioned to the rear of the presser foot and comprising a member having a down turned front end portion coacting with said slot and having a resilient opposite rear end portion extending away from said slot and from the needle of said machine, said resilient rear end portion of said member being provided with a cutting side edge disposed closely adjacent and approximately parallel to said frame.

9. In combination with a sewing machine having a presser foot and a work supporting surface provided with a slot, a thread cutter positioned to the rear of the presser foot and comprising a member having a down turned front end portion coacting with said slot and having an opposite resilient rear end portion extending away from said slot and from the needle of said machine, said member extending away from said needle in the direction of travel of material past said needle and having a cutting edge at its rear outer side edge closely adjacent to said surface.

10. In combination with a sewing machine having a presser foot and a work supporting surface between the needle and the bobbin thereof, a thread cutter for the needle and bobbin threads of said machine positioned on the work supporting surface entirely to the rear of the presser foot and comprising a member having a resilient rear end portion adapted to receive said threads and to yieldingly hold the ends thereof between said resilient rear end portion and the work supporting surface by frictional tension, means for regulating said frictional tension, said member also having a thread severing portion at its rear outer side edge closely adjacent and approximately parallel to said work supporting surface.

In testimony whereof, I affix my signature.
CHARLES W. H'DOUBLER.
